DOOR LATCH

Filed Feb. 17, 1920

UNITED STATES PATENT OFFICE.

SAMUEL B. GARNER, OF BEND, OREGON.

DOOR LATCH.

Application filed February 17, 1920. Serial No. 359,465.

To all whom it may concern:

Be it known that I, SAMUEL B. GARNER, a citizen of the United States, and a resident of Bend, county of Deschutes, State of Oregon, have invented a new and useful Improvement in Door Latches, of which the following is a specification.

The object of my invention is to provide a latch that is compact and simple in construction and is contained within a cylinder casing which can be placed within holes bored by a common auger in the edge and sides of the door thus almost totally eliminating the mortising of the door that is required for the ordinary door latch. One of the main features of my device is that it is so constructed that it can be operated by merely bearing against the door knob on one side or pulling the door knob upon the opposite side, but at the same time holding the door in its latched position and preventing the same from being opened by any pressure against the door itself. It is also my desire to provide auxiliary means for causing the latch to act as a positive lock.

I attain the above described and incidental features in the device hereinafter described and illustrated in the accompanying drawings.

30 In the drawings:—

Fig. 1 is a perspective view of a door showing the holes that are bored for the insertion of my door latch;

Fig. 2 is a perspective view of the door casing showing the hole bored for the latch stop;

Fig. 2^a is a perspective view of the latch stop;

Fig. 3 is a perspective view of my door latch arranged in similar manner as the parts would be positioned in the cavities or holes provided therefor in the door;

Fig. 4 is a plan section taken on the line 4—4 of Fig. 3;

Fig. 5 is an inverted vertical half section taken on the line 5—5 of Fig. 3, looking in the direction indicated by the arrow;

Fig. 6 is a cross section on the line 6—6 of Fig. 4, looking in the direction indicated by the arrow;

Fig. 7 is a cross section on the line 7—7 of Fig. 5;

Figs. 8, 9, 10 are detailed views of parts of my latch;

Fig. 11 is a section on the line 11 of Fig. 3;

Fig. 12 is section on the line 12—12 of Fig. 3;

And Figs. 13, 14 are perspective views of the parts shown in Figs. 11 and 12.

The construction of my device is as follows:

A tubular casing *a*, having at one end a face plate *b*, is closed at the other end by screw cap *c*. The face plate *b* has a square opening *d*, thru which projects the latch *e*, 65 of the latch mechanism and a section of the casing *a*, is cut away as at *a'*.

The latch *e* (see Fig. 8) consists of a solid portion *f*, from which project a pair of flanges *g*. The side of one of the 70 flanges, together with the corresponding side of the portion *f*, forms a parallelogram and the flange constitutes more than one-half of the length of the long axis of the parallelogram thus formed.

Holes *h* are bored thru the flanges at the intersection of the long and short axis as shown in Fig. 8. The channel shaped member *i* provided at one end with the projecting portions *j*, thru which are bored the 80 holes *k*, is pivotally mounted to the latch *e*, between the flanges *g* with the holes *h*, *k* alining and a bolt *l* passing thru the same

The bar shaped member *m* has at one end an enlarged portion *n* thru which is bored 85 a hole *o*, and is pivotally mounted to the latch *e* between the flanges, with the hole *o* alined with the holes *p* bored thru the flanges *g* in the line of the short axis and a bolt passes thru the same.

The free ends of the member *i* and *m* are slidably mounted within a square tube *q* which is of a shorter length (see Figs. 4 and 5) and extends only part way over the same, thus excluding the latch *e*. 90

The lug *r* sets within the square hole *s* which is cut in the lower side of the member *q*, and is held firmly within the same by means of the spring *t*, which is bolted to the surface of the member *m*, and bears 100 against the under surface of the top portion of the member *i*.

The lug *r*, which is a part of the member *m*, is allowed a slidable relation with the member *q* except when the lug *r* is in the hole *s*. The members *i*, *q* and *u* are then all fastened together by the lug *r* being in the hole *s* and there can be no relative motion between them, but when the lug *r* is raised from the hole *s* the members *i* and *m* can 110

- move relatively with the member *q* and the latch *e* can assume the position shown in dotted lines in Fig. 4, and thus pressure on the door will cause the latch to be released.
- 5 The circular pin *n'* holds the members *q* and *i* together.

This combination is then inserted into a cylindrical tube *u* and when in place the tube *u* is secured firmly in this position by 10 spot welding as at the corners *q'*, and thus the members *q* and *u* are firmly locked together.

The latch mechanism as thus shown is then slidably mounted within the casing *a* thru the opening in the end of the same, and is placed in the position as shown in Figs. 15 4 and 5, with the latch *e* protruding thru the opening *d* in the face-plate *b*.

A coil spring *v* is mounted on the pin *w* 20 which in turn is secured to the lug *x* mounted on the surface of the bearing member *m*. This spring bears against the inner side of the cap *c* and tends to hold the latch mechanism in its forward position as shown in 25 Fig. 4. The assembled latch mechanism is then inserted into the hole *y* bored in the end of the door and the section as *b'* is then mortised out of the face plate *b*.

The latch mechanism operates as in a 30 standard latch and thus can be forced inwardly either by bearing against the end of the latch or against the inclined face *e'* of the latch *e*. The flat face *e''* of the latch *e* bears against the side *2'* of the square hole 35 3 cut in the latch stop 2. (See Fig. 2^a.)

As stated before it is my intention to provide means for operating the latch by merely pulling or bearing against the door knob and to accomplish this result I rigidly attach to 40 the square slide bar 4, on the ends of which are mounted the knobs 4', the member 5 having a perpendicular projecting arm 6. This slide bar 4 is set within the hole 7 bored in the side of the door 2 directly over the 45 opening *a'* of the casing *a*. The holes 8 and 9 are then bored directly underneath but with the center of each hole closer together than the diameter of each. The portion as indicated by 10 is cut away thus providing 50 for the vertical face 11.

The latch stop 2 is inserted into the section 12 mortised out in the door casing 13.

As will be seen in Fig. 7 the arm 6 sets directly before and almost bears against 55 the stud 14 mounted on the end of the member *m*. (See Fig. 10.) When the slide bar 4 is pressed back into the casing the bar member *m* assumes the position shown by the dot and dash line *m'*.

60 The lug *r* is thus lifted out of the opening *s* and the latch *e* together with the latch mechanism is then free to be moved forward as shown by dot and dash lines in Fig. 4, and the latch *e* assumes the position as 65 shown. The face *e''* thus becomes an in-

clined plane and the edge *2'* bearing against the same forced the latch inward.

When the door is again closed the side *3'* of the opening 3 bears against the face *e'* and forces the latch to assume its original 70 position and the lug *r* again sets within the hole *s*.

The door can thus be opened by pushing or pulling the knobs but resists any pressure 75 against the door itself.

As stated before, one of the main objects of my invention is to provide for simplicity, compactness in construction and the small number of parts used; and also a device with parts so shaped that it is only necessary to 80 drill holes in the door together with a very small amount of mortising.

To obtain this object I provide means for having the latch function also as a positive lock to be operated by a key, that the door 85 cannot be opened by means of the knobs and accomplish the same by the following means.

The circular member 15 (see Figs. 11, 12, 13 and 14) has a projecting portion 16 in which is cut a dove-tailed groove 17. The 90 bar 18 on which are mounted the lugs 19 and 20 inclined as shown, sets within the groove 17 and is free to slide within the same. To limit the movement of the same, I provide a pin 21 set in a hole 22 in the bar 95 18 and sliding in a groove 23 cut in the back of the portion 16 of member 15. The member 15 is then inserted into the casing 24 closed at one end as 25 and with slots 26 provided for bar 18. An opening 27 is provided for the key 28.

The casing 24 is set within the hole 11 in the door 2 in the position relative to the latch casing *a* as shown in Fig. 3. The end of the bar *m* sets only part way beyond the 105 opening *a'*, thus providing for a space behind the same as 30 and in which slides the member 18.

The projecting lug 28' of the key 28 raises the member 18 by bearing against the underside of the stud 19 when the key is turned and the member then sets between the end of the bar *m* and the side of the opening *a'* in the casing *a* and prevents the movement 115 of the latch mechanism, thus locking the same as seen in Fig. 3.

The lug 28 bears against the lug 20 when the key 28 is turned in the opposite direction and thus unlocks the latch mechanism.

I claim:

1. In a device of the character described, the combination of a tubular casing, a member supported in the casing and longitudinally slidably therein, a triangular latch-piece pivoted at one of its vertices to one 125 end of said member, a spring actuated bar pivoted to said latch, and adapted to hold the latter in one position, means locking said bar against longitudinal movement, thereby preventing the movement of the 130

latch on its pivot, such locking means being adapted to release the bar by lateral pressure against the latter.

2. In a device of the character described the combination of a tubular casing, a member supported in the casing and longitudinally slid able therein, a triangular latch-piece pivoted at one of its vertices to one end of said member, a spring actuated bar pivoted to said latch, and adapted to hold the latter in one position, spring controlled means locking said bar against longitudinal movement, thereby preventing the movement of the latch on its pivot, such locking means being adapted to release the bar by lateral pressure against the latter.

3. In a device of the character described the combination of a tubular casing, a member supported in the casing and longitudinally slid able therein, a triangular latch-piece pivoted at one of its vertices to one end of said member, a spring actuated bar

pivoted to said latch, and adapted to hold the latter in one position, means locking said bar against longitudinal movement, thereby preventing the movement of the latch on its pivot, and a door knob shank provided with a piece adapted to bear against, and thereby laterally move said bar.

4. In a device of the character described, the combination of a tubular casing, a member supported in the casing and longitudinally slid able therein, a triangular latch-piece pivoted at one of its vertices to one end of said member, a spring actuated bar pivoted to said latch and adapted to hold the latter in one position, spring controlled means locking said bar against longitudinal movement, thereby preventing the movement of the latch on its pivot, and a door knob shank provided with a piece adapted to bear against, and thereby laterally move said bar.

SAMUEL B. GARNER.
